Des. 225,791
Patented Jan. 2, 1973

225,791

TRANSPARENT PHOTOGRAPH ALBUM PAGE

Robert Nast, 942 Glenridge Ave.,
North Woodmere, N.Y. 11598

Filed Feb. 28, 1972, Ser. No. 230,200

Term of patent 14 years

Int. Cl. D19—04

U.S. Cl. D97—1

FIG. 1

FIG. 2

FIG. 3

FIG. 4

FIG. 5

FIG. 6

FIG. 7

FIG. 1 is a perspective view of a transparent photograph album page showing my new design, the page having two negative pockets and four photograph print pockets;

FIG. 2 is a top plan view thereof; and
FIG. 3 is a bottom plan view thereof;

FIG. 4 is a perspective view of another embodiment of the transparent photograph album page shown in FIG. 1, the page having two negative pockets and six photographic print pockets;

FIG. 5 is a top plan view thereof;

FIG. 6 is a bottom plan view thereof; and

FIG. 7 is an enlarged section taken along line 7—7 of FIG. 5.

I claim:

The ornamental design for a transparent photograph album page, substantially as shown and described.
